DESIGN FOR A MIMEOGRAPH EQUIPMENT BOARD

Katherine F. Walker, Sioux City, Iowa

Application November 21, 1938, Serial No. 81,275

Term of patent 3½ years

To all whom it may concern:

Be it known that I, Katherine F. Walker, a citizen of the United States of America, residing at Sioux City, in the county of Woodbury and State of Iowa, have invented a new, original, and ornamental Design for a Mimeograph Equipment Board, of which the following is a specification, reference being had to the accompanying drawing, forming a part thereof.

In the drawing, the figure is a perspective view of a mimeograph equipment board, showing my new design.

The design comprises a flat rectangular base having an elongated oval-shaped depression near its forward edge with an irregular shaped depres-

sion at one end of the oval and parallel transverse depressions separated by a shallow groove at the other, there being circular depressions near the rear corners of the base with small openings between the circular depressions and disposed in staggered relation to each other, the circular depressions and oval-shaped depressions being separated by a plurality of narrow longitudinal grooves, one of which is shorter than the others with its opposite ends converging in the direction of the oval depression.

I claim:

The ornamental design for a mimeograph equipment board, as shown and described.

KATHERINE F. WALKER.
